Co., Inc., Attleboro, Mass., a corporation of
Massachusetts

Application May 3, 1940, Serial No. 333,214

6 Claims. (Cl. 70—459)

This invention relates to a key ring, and it consists in the constructions, arrangements and combinations herein described and claimed.

It is an object of the invention to provide a key ring of novel construction in which sharp corners are avoided, thus eliminating wear of the pockets of a garment when carried therein.

It is a further important object of the invention to provide a novel means for locking keys upon the ring, yet readily movable to a position to permit removal of a key or the application of additional keys thereto.

More particularly it is an object of the invention to provide a split key ring and a slide, the latter having a means cooperable with the slot of the ring to effect locking of the ring against movement, with consequent retention of keys upon the ring.

Additional objects, advantages and features of the invention will be apparent from the following description and accompanying drawing, wherein

Figure 1 is a side elevation of the key ring as secured to a conventional showing of key chain.

Figure 2 is an enlarged view of the ring, showing the locking means in its operative position.

Figure 3 is a vertical sectional view thereof.

Figure 4 is a view similar to Figure 2, illustrating the locking means in its inoperative position.

Figure 5 is an enlarged fragmentary vertical section thereof.

Figure 6 is an enlarged fragmentary elevation illustrating the slide and ring with the locking means removed.

Attention is first invited to Figure 1 of the drawing, wherein we have illustrated a key chain 10 of any suitable construction having at one end an attaching ring 11 for securing of the chain to a belt loop or the like, as well understood. The other end of the chain 12 terminates in a novel construction of link 13 within which a tubular slide 14 is engaged, as will now be described.

Reference is now made to Figures 2 and 3, for an understanding of the construction of the ring 15, the slide 14 and the link 13. The ring 15 as shown, is of annular form, and may be of any desired cross sectional contour, in the present instance being shown as substantially oval. The ring 15 is of split formation, the ends 16 being aligned, but stopping short of one another, defining a space 17. The space 17 is of a width only slightly greater than the greatest cross sectional area of the link 13, as will be presently explained.

The slide 14 is of tubular arcuate formation

and has a cross sectional shape of the ring 15. The slide 14 is slidably engaged upon the ring so that it may be freely moved therearound and preferably the slide is of a length approximately one-third the circumference of the key ring 15, although this is not arbitrary, since the dimensions of the ring and slide will vary for different uses of the key ring.

As clearly shown in Figure 6, the slide 14 has formed in its outer wall a semi-circular transverse recess 18, the recess being positioned intermediate the ends of the slide. The slide includes a plate 19, formed integrally with the outer wall thereof, or separate as desired, the latter form being shown, in which event the plate will be soldered or otherwise secured to the slide. The plate 19 has a semi-circular recess 20 complementary to the recess 18, thus forming an annulus for reception of the link 13.

The link 13 is clearly shown in Figures 2, 3, 20 and 5 and consists of a closed ring formed in the shape of the numeral 8 from a suitable length of wire, the wire having a tapering formation from a thick bight portion 21 toward a thin medial bight portion 22. The thick bight portion 21 is of a thickness but slightly less than the space 17 so that when the link 13 is in the position shown in Figures 2 and 3, the bight will be readily receivable in the space 17 between the ends 16 of the key ring. In such position

it will be apparent that the slide 14 is locked or secured against sliding movement upon the key ring 15. When it is desired to release the slide 14 to expose the slot 17 for removal or replacement of keys on the ring 15, the link 13 is moved to a right angular relation with respect to the slide as indicated in Figure 5, the link being given a transverse movement, thus bringing the reduced medial portion 22 to a position within the slot 17. As may be seen in Figure 5, the portion 22 has a slight frictional engagement with the recessed portion 20 of the plate 19 to hold the link in proper position, yet the diameter of the portion 22 is such as to freely lie within the recess 20 and the outer periphery of the key ring 15, as shown in Figure 4. Obviously, the slide may then be moved circumferentially of the ring 15 to expose the slots when the keys may be added to or removed from the ring.

In order that the slide 14 may be readily brought into proper position with respect to the slot 17, the ring 15 is provided with a stop collar 23.

While we have shown and described a preferred construction, this is by way of illustration only,

and we consider as our own all such modifications in structure as fairly fall within the scope of the appended claims.

We claim:

- 5 1. A key ring comprising a ring having spaced ends, a tubular slide on the ring, a recess in a periphery of the slide, and a link carried by the slide and seated within the recess, said link having a thickness at one end to engage said ring between the spaced ends to prevent movement of the slide, another portion of the link having a thickness to permit free movement of the slide when said portion or closely adjacent part is moved in registration with the spaced ends of the ring.
- 10 2. A key ring comprising a ring having spaced aligned ends, a tubular slide on the ring, a recess in a periphery of the slide, said slide having a portion complementary to the recess defining an annulus, a link movably mounted within the annulus, said link having a thickness at one end freely, yet snugly engaged between the spaced ends of the ring to prevent movement of the slide, and another portion of the link having a thickness to permit free movement of the slide when said portion or closely adjacent part is moved in registry with the spaced ends of the ring.
- 15 3. A key ring comprising a ring having spaced aligned ends, an arcuate tubular slide on the ring, a recess in the outer periphery of the slide, a plate on the slide, said plate having a recess complementary to the recess of the slide defining an annulus, a link movably mounted within the annulus, said link having a thickness at one end freely, yet snugly engaged between the spaced ends of the ring to prevent movement of the slide, and another portion of the link having a thickness to permit free movement of the slide when said portion or closely adjacent part is moved between the spaced ends of the ring, and stop means on the ring for limiting sliding movement of the slide.
- 20 4. A key ring comprising a ring having spaced aligned ends, an arcuate tubular slide on the ring, a recess in the outer periphery of the slide, a plate on the slide, said plate having a recess complementary to the recess of the slide defining an annulus, a link movably mounted within the annulus, said link having a thickness at one end freely, yet snugly engaged between the spaced ends of the ring to prevent movement of the slide, said link having a tapering formation to define a bight portion of reduced cross sectional area, to permit free movement of the slide when said bight or adjacent portion is moved in registration with the spaced ends of the ring, and stop means on the ring for limiting sliding movement of the slide.
- 25 5. A key ring comprising a ring having spaced aligned ends, an arcuate tubular slide on the ring, a recess in the outer periphery of the slide, a plate on the slide, said plate having a recess complementary to the recess of the slide defining an annulus, a link movably mounted within the annulus, said link having a thickness at one end freely, yet snugly engaged between the spaced ends of the ring to prevent movement of the slide, said link having a tapering formation to define a bight portion of reduced cross sectional area, to permit free movement of the slide when said bight or adjacent portion is moved in registration with the spaced ends of the ring, and stop means on the ring for limiting sliding movement of the slide.
- 30 6. A key ring comprising a ring having spaced aligned ends, an arcuate tubular slide on the ring, a recess in the outer periphery of the slide, a plate on the slide, said plate having a recess complementary to the recess of the slide defining an annulus, a link movably mounted within the annulus, said link having a numeral 8 formation, one end of the link having a thickness freely, yet snugly engaged between the spaced ends of the ring to prevent movement of the slide and of tapering formation in the direction of the other end of the link having slight frictional engagement with the recess of the plate when moved thereinto to permit movement of the slide between the ends of the ring, and stop means on the ring for limiting sliding movement of the slide.
